(57) **CLAIM**

The ornamental design for a driving gaming device cabinet, as shown and described.

DESCRIPTION

FIG. 1 is a front perspective view of the driving gaming device cabinet of our new design.

FIG. 2 is a rear perspective view of the driving gaming device cabinet of our new design illustrated in FIG. 1.

FIG. 3 is a front view of the driving gaming device cabinet of our new design illustrated in FIG. 1.

FIG. 4 is a back view of the driving gaming device cabinet of our new design illustrated in FIG. 1.

FIG. 5 is a right side view of the driving gaming device cabinet of our new design illustrated in FIG. 1.

FIG. 6 is a left side view of the driving gaming device cabinet of our new design illustrated in FIG. 1.

FIG. 7 is a top view of the driving gaming device cabinet of our new design illustrated in FIG. 1; and,

FIG. 8 is a bottom view of the driving gaming device cabinet of our new design illustrated in FIG. 1.

The broken lines shown on the driving gaming device cabinet form no part of the claimed design.

1 Claim, 8 Drawing Sheets(56)
